UNITED STATES PATENT OFFICE.

LINUS G. ANDERSON, OF SIOUX CITY, IOWA.

HAIR-TONIC APPLICATOR.

Application filed February 17, 1925. Serial No. 9,837.

My invention relates to a device for applying tonics and the like to the scalp and hair of a person, and it is my object to provide such a device which is of simple, durable and inexpensive construction.

A further object is to provide a manually operated applicator having the general form of a comb.

A further object is to provide such an applicator which is provided with a container for the tonic or liquid used in connection therewith, and a delivery pipe having a series of spaced nozzles to eject the liquid, and a control valve for said delivery pipe situated for convenient access to the hand of the operator.

A further object is to provide such an applicator having a casing provided with individual sleeves enclosing the delivery pipe nozzles, together with a resilient hand bulb adapted to supply air under pressure to said casing, the ends of the sleeves being provided with exhaust openings, so positioned adjacent the ends of the discharge nozzles that the action of the air escaping therethrough under pressure from the handle will atomize the liquid within the discharge pipe and convey it through said exhaust openings.

Another object is to so form the ends of the casing sleeves that the delivery of the liquid may be so controlled as to permit its being deposited either directly against the scalp or upon the hairs at a distance above the scalp.

Another object is to provide certain novel features of construction whereby the hand bulb may be readily removed and the operative parts of the applicator readily made accessible for cleaning or repair, and whereby the device may be constructed in a simple and inexpensive manner.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is an elevation of the applicator.

Fig. 2 is a longitudinal vertical sectional view of the same.

Fig. 3 is a detail transverse sectional view taken on the line 3--3 of Fig. 2.

Fig. 4 is a detail transverse sectional view of the same taken on the line 4--4 of Fig. 2.

Fig. 5 is a plan view of a portion of the applicator, the bulb being shown in section.

I have used the reference character 10 to indicate generally a casting which forms the inner frame structure of my device. The casting, 10, may be of brass or aluminum, or of hard rubber, and at one end is cast integrally with the comb portion of the applicator, which I will indicate generally by the reference character, 11, and which is preferably formed of sheet metal. The portion 11 includes a liquid delivery pipe, 12, having the discharge nozzles, 13, and embedded at one end in the casting, 10.

The pipe, 12, is preferably formed of tubing, the nozzles, 13, being tubes of fine bore, swaged or soldered into the wall of the tube, 12. The liquid chamber, 14, is formed between the walls of a plate of sheet metal, doubled upon itself, as at 15, to form the container sides, 16, which are thence bent inwardly, as at 17, and soldered to the sides of the tube, 12, and thence extended downwardly, as at 18, to form the air casing. The tube, 12, serves to separate the chamber, 14, from the air casing, 18.

The nozzle sleeves are formed by splitting the metal extending downwardly from the air casing, 18, and thence drawing the edges of the severed portions inwardly against the edges of the adjoining portions on the other side, as at 19. I have used the reference character 20 to indicate the sleeve portion formed on one side of the casing, 18, and the numeral 21 to indicate the adjoining sleeve portion.

A tongue is formed on the portion, 21 and bent inwardly against the end edges of the sleeve portions to form an end wall, 22. When the casing is completed the end wall, 22, is inclined as shown in Fig. 3 and is provided with an opening, 23, substantially aligned with the nozzle, 13. The advantages of so inclining the ends of the sleeves will later be more fully explained.

To give the applicator a finished appearance two dummy teeth, 24 and 25, may be formed at the extremity of the comb portion thereof.

The lower edges of the casing portion, 18, between the nozzle sleeves and between the tooth, 25, and the casting, 10, as well as the outer ends of the walls, 16, and the tooth,

24, are drawn together to form a closed structure. The entire member, 11, may then be soldered to close the joints, or cleaned and dipped in an enamel coating of a coating of rubber composition. This is necessary in order to render the applicator sanitary.

10 The outer end of the tube, 12, is soldered or swaged into the end wall of the member, 11, as shown in Fig. 2, and a threaded plug, 26, serves to close the tube and to allow cleaning thereof.

15 The cavity, 27, in the casing, 10, communicates by means of a threaded opening, 28, with a duct, 29, which forms a continuation of the tube, 12. A neck, 30, having a threaded opening at its upper end communicates with the cavity, 27, and is normally closed by a plug, 31, threaded thereto. Removal of the plug, 31, allows filling of the 20 container, 14.

25 The casting, 10, is bored and tapped to receive a threaded valve member, 32, having a lower conical end seating against the shoulder formed between its threaded portion and the smaller threaded opening, 28. Thus, the valve member serves to close or control the passage of liquid through the opening, 28, and may be removed to allow 30 cleaning thereof. Cleaning of the passage leading from the cavity, 27, to the opening, 28, may be effected through the neck, 30, and cleaning of the tube, 12, and the passage leading therefrom is facilitated by the 35 lengthening of the duct, 29, beyond the opening, 28, to allow a cleaning tool to extend beyond the opening, 28.

40 The casting, 10, is provided with a handle portion, 33, paraboloidal in shape, as shown in Fig. 5, and provided with the reduced neck portions, 34, and 35, spaced to receive the ends of a rubber bulb, 36.

45 Into the end, 35, is threaded a cap, 37, which serves both to retain the bulb, 36, in place and to enclose a check valve, 38, in the passage, 39, which communicates with a passage, 40, in the handle portion, 33, allowing the entrance of air through the passage, 39, into the bulb, 36. An opening, 41, provides communication between the bulb, 36, and the air casing, 18, and is provided at its discharge end with a check valve, 42.

50 It will now be seen that after filling the chamber, 14, with liquid, a quantity thereof may be allowed to escape into the delivery pipe, 12. By compressing and releasing the bulb, 36, a current of air may be created through the enclosing sleeves and the liquid drawn through the tubes, 13, similar to the 55 action of the ordinary atomizer.

55 In order to allow entrance of air into the chamber, 14, to replace the liquid the plug, 31, is provided with a passage, 43, which may be closed when the applicator is 60 not in use. By tightening the plug, 31,

against the neck, 30, and thus sealing the chamber, 14, the liquid will be effectually sealed within the container and leakage will be prevented.

65 The tubes, 13, are of such gauge that the liquid will not pass through them except when the pipe, 12, is in communication with the atmosphere through the opening, 43.

70 By applying the tips of the sleeves to the scalp with the comb tilted so as to allow a flat contact of the end walls, 22, with the scalp, it will be seen that the liquid may be applied directly to the scalp. By tilting the comb in the other direction, at an angle to the scalp, and allowing the extreme tips 75 to contact with the scalp, the openings, 23, being thereby raised from the scalp and directed laterally with respect thereto, the liquid may be sprayed among the hairs at 80 a distance from the roots thereof.

85 It will be understood that my applicator may be used for various purposes aside from that of applying hair tonics and hair oils, such as for shampooing or dyeing the hair.

90 Some changes may be made in the construction and arrangement of the parts of my invention without departing from the real spirit and purpose of my invention, and it is my intention to cover by my claims any 95 modified forms of structure or use of mechanical equivalents which may be reasonably included within their scope.

I claim as my invention:

1. A hair tonic applicator comprising a 100 comb portion, said comb portion being hollow and provided with teeth, a tube extending longitudinally through said comb portion and secured to the sides thereof so as to form a liquid container above said teeth, means for transferring air under pressure 105 to the interior of said teeth, nozzles carried by said tube and extending into said teeth, a passageway being provided to allow liquid in limited quantities to flow from the container into said tube.

110 2. A hair tonic applicator comprising a comb portion, said comb portion being hollow and provided with teeth, a tube extending longitudinally through said comb portion and secured to the sides thereof so as to form a liquid container above said teeth, means for transferring air under pressure 115 to the interior of said teeth, nozzles carried by said tube and extending into said teeth, a passageway being provided to allow liquid in limited quantities to flow from the container into said tube, and a valve controlling 120 said passageway.

3. An applicator having a series of hollow 125 teeth arranged in the form of a comb, a handle member including a rubber bulb in connection with said teeth, a container, and means for delivering liquid from said container to the tops of said teeth, said means including a delivery pipe communicating be- 130

tween the container and the teeth, and a needle valve adapted to regulate the flow of liquid to said delivery pipe.

4. An applicator comprising a hollow comb-shaped air casing having hollow teeth, a handle member mounted in one end of said casing, a delivery tube mounted in the other end of said casing and in said handle, nozzles in said delivery tube extending into said teeth, said tube being secured to the sides of the casing so as to form a liquid container therein, above the teeth, the handle member being provided with passages communicating with the delivery tube and liquid container, respectively, and with a connecting passage extending between said first mentioned passages to allow liquid to flow in limited quantities from the container to the tube.
- 10 5. An applicator comprising a hollow comb-shaped air casing having hollow teeth, a handle member mounted in one end of said casing, a delivery tube mounted in the other end of said casing and in said handle, nozzles in said delivery tube extending into said teeth, said tube being secured to the sides of the casing so as to form a liquid container therein, above the teeth, the handle member being provided with passages communicating with the delivery tube and liquid container, respectively, and with a connecting passage extending between said first mentioned passages to allow liquid to flow in limited quantities from the container to the tube, and with a valve controlling
- 15
- 20
- 25
- 30

necting passage extending between said first mentioned passages to allow liquid to flow in limited quantities from the container to the tube, and a rubber bulb supporting and supported upon said handle member, the handle member being provided with a passage communicating with said bulb and with the interior of the toothed portion of the air casing.

6. An applicator comprising a hollow comb-shaped air casing having hollow teeth, a handle member mounted in one end of said casing, a delivery tube mounted in the other end of said casing and in said handle, nozzles in said delivery tube extending into said teeth, said tube being secured to the sides of the casing so as to form a liquid container therein, above the teeth, the handle member being provided with passages communicating with the delivery tube and liquid container, respectively, and with a connecting passage extending between said first mentioned passages to allow liquid to flow in limited quantities from the container to the tube, and a valve controlling

Signed at Sioux City, in the county of Woodbury and State of Iowa, this 11th day of February, 1925.
